UNITED STATES PATENT OFFICE.

FRANK S. INGOLDSBY, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

STOP.

1,004,267.

Specification of Letters Patent. Patented Sept. 26, 1911.

Application filed April 4, 1907. Serial No. 366,404.

To all whom it may concern:

Be it known that I, FRANK S. INGOLDSBY, a citizen of the United States, residing at St. Louis, State of Missouri, have invented a 5 certain new and useful Improvement in Stops, of which the following is a full, clear, and exact description, reference being had to the accompanying drawings.

The object of this invention is to provide 10 a simple, cheap and easily applied stop to limit the movement of an adjacent member.

The stop is adapted for a variety of uses and is especially applicable in mechanism 15 where there is a member liable to be displaced, as for example, a member on a shaft where there is some jarring longitudinally of the shaft or other force tending to displace the member.

20 As a particular use for the stop, I may cite its application to the door raising mechanism of dump cars wherein there are longitudinal shafts having raising arms, and these arms are liable to become displaced 25 when the cars are violently coupled together.

My invention not only locks the member in place preventing shifting, but also locks the bolt which secures the stop.

30 The invention comprises the means by which I effect the above results. It is illustrated in the drawings hereof in a preferred form, which form is hereinafter fully described.

35 In the drawings, Figure 1 is a side elevation of a portion of a shaft having keyed to it an arm and equipped with my stop, the final position of the stop being shown in full lines, and the original position of its 40 free end in dotted lines. Fig. 2 is a similar view showing the position the stop takes when the arm cannot be forced into its regular position. Fig. 3 is a plan of the stop and its bolt, being in plane at right 45 angles to Figs. 1 and 2 and looking down with reference to these figures. Fig. 4 is a section on the line 4—4 of Fig. 1. Fig. 5 is a perspective view of the stop removed.

Referring to the embodiment shown in the 50 drawings, 10 represents a shaft and 11 an arm or other member embracing the same and keyed thereto by the key 12 which occupies a keyway 13 in the shaft. This keyway comes to an abrupt shoulder 14 at one

end and the large end of the key rests 55 against such shoulder.

The stop member itself is indicated by 15, and consists of a sheet metal strip bent back and forth on itself, as shown. It is provided with a hole 16 through which passes 60 a bolt 17 which secures the stop to the shaft on the side of the arm corresponding to the small end of the key, that is, on that side toward which the arm might move, the taper of the key preventing the arm moving 65 in the other direction.

When the stop is applied it is in the form shown in Fig. 5, having its extreme portion 18 standing above the rest of the stop, as shown also in dotted lines in Fig. 1. After 70 the stop in this condition has been secured to the shaft by the bolt, or tap-screw, 17, the portion 18 of the stop is hammered down coming into the final position shown at 19 in Fig. 1, and engaging at its extreme 75 end with the head 20 of the bolt and at its first bend with the side of the arm 11. It will be seen that in this position the stop not only prevents the arm having any movement, but acts as a lock for the bolt, preventing 80 it being unscrewed.

If the arm does not come into its extreme position shown in Fig. 1 (which may frequently result in comparatively rough work) the portion 18 of the stop may take 85 the position shown in Fig. 2. In this position the stop acts also to hold the arm against displacement and to lock the bolt in the same manner it would if the parts came to their preferred position. If the 90 arm should fall considerably short of attaining its preferred position, the end of the portion 18 of the stop may be easily cut off with a cold chisel to allow it to be bent down into position. The head of the bolt 95 makes an excellent anvil on which to cut off the end of the member 18 when this is necessary. Where the range of variations for the arm is small, the portion 18 need never be cut off and still may accommodate a 100 number of positions of the arm.

There are two objects in making one or more folds of the stop under the head of the tap-screw as indicated by 21. First, these folds give more metal in shear against 105 the shank of the screw, and second, they raise the outer arm 18 and the next ply 22 high enough to pass over the top of the key

so that there will be no trouble in flattening the portion 18.

My stop is cheaply constructed and easily applied. It is simply necessary to turn in the tap screw and hammer down the portion 18 of the stop. When so placed, the arm and tap screw are both locked securely into position, while to remove the parts it is only necessary to pry up the portion 18 of the stop.

Having thus described my invention, I claim:

1. The combination, with a member, of a stop formed of a strip of sheet metal bent on itself, and a bolt having an angular head and arranged to secure said strip in such position that it may engage said member and at the same time engage the head of the bolt.

2. The combination with a supporting member and a second member thereon, of a stop consisting of a metal strip bent back and forth on itself, and means for securing the same to the supporting member, said stop being adapted to engage said second member.

3. A stop made of a strip of sheet metal bent back and forth on itself and having its final portion free and adapted to be brought closer to the adjacent portion and parallel therewith, combined with means for securing the stop adapted to be engaged by such portion.

4. The combination with a supporting member and a second member thereon, of a stop comprising a sheet metal strip bent back and forth on itself and secured to the supporting member and adapted to engage the second mentioned member, and also lock the means for securing the stop.

5. The combination with a supporting member and a second member thereon, of a stop consisting of a metal strip bent on itself, a bolt for fastening the stop to the supporting member and adapted to engage the second mentioned member and also engage and lock the bolt for securing the strip.

6. The combination of a shaft having a key-way, a tapered key occupying said key-way, a member held against rotation by the key, a stop, means for securing the stop to the shaft, said stop adapted to engage said member and also lock the securing means.

55 7. The combination of a shaft having a key-way coming to an abrupt shoulder, a tapered key occupying such key-way with its large end against said shoulder, a member surrounding the shaft and said key, and a stop bolted to the shaft on the side where the small end of the key is, said stop being adapted to lock the member against movement toward the stop and also lock the bolt against unscrewing.

65 8. The combination of a shaft having a

key-way, a key occupying said key-way, a member surrounding said shaft and key, a stop comprising a strip of metal bent on itself and bolted to the shaft, said strip having a free portion adapted to be hammered down between the side of the member and the head of the bolt.

70 9. The combination of a shaft having a key-way, a key occupying said key-way, a member surrounding said shaft and key, a stop comprising a strip of metal bent back and forth on itself and secured to the shaft, said strip having a free portion adapted to be hammered down against the side of the member, said strip bending on itself 80 times enough to raise the free portion above the end of the key.

75 10. The combination of a shaft, a member slideable along the same, means for limiting the movement of said member in one direction, a stop for limiting the movement in the other direction, said stop consisting of a sheet metal strip bent on itself, means for securing said stop to the side of said shaft and parallel therewith, the stop engaging 90 and preventing displacement of the securing means.

85 11. The combination of a member, a second member movable thereon, a stop for limiting the second member, a bolt for securing the stop in position, said bolt having an angular head, and the stop engaging the second member and standing in the path of rotation of said angular head.

95 12. The combination of a shaft, a member 100 slideable thereon, a stop for limiting the movement of said member, a bolt passing through said stop and screwing into the shaft for securing the stop in place, said bolt having an angular head and said stop 105 being adapted to limit the movement of the member in that direction and to also stand in the path of rotation of said head.

110 13. The combination of a shaft, a member surrounding the same and slideable thereupon, means for limiting the movement of said member in one direction, a stop for limiting the movement of the member in the opposite direction, a bolt for securing said stop to said shaft, said stop being adapted 115 to engage the member and engage also the bolt, preventing the movement of the member and the rotation of the bolt.

120 14. The combination of a member, a second member slidably mounted thereon, a stop for limiting the movement of the said second member, said stop consisting of sheet metal bent back and forth upon itself and having its final bend free and adapted to be brought parallel with the adjacent bend, 125 and means for securing the stop, said stop engaging and holding both the second member and its own securing means.

130 15. The combination of a shaft, a member surrounding the same, a key for preventing

rotation of the shaft relative to the surrounding member, a stop for preventing longitudinal movement of said member, said stop being secured to the shaft and engaging said member and locking its own securing means.

16. The combination of a shaft, a member surrounding the same, a key preventing independent rotative movement of the member and shaft, a bolt screwing into the shaft, and a stop held in place by said bolt and limiting the longitudinal movement of said member, said stop itself preventing the screwing out of said bolt.

17. The combination with a shaft, of a member thereon adapted to slide along the same, a metallic strip mounted upon said shaft and bearing against the said member, and means extending through the strip and secured in the shaft for holding the strip in place, said strip being adapted to hold the said means against dislodgment.

18. The combination with a shaft, of a

member thereon adapted to slide along the same, a key for preventing independent rotation of the member upon the shaft, a metallic strip mounted upon the shaft engaging with the member above the key, a member extending through said metallic strip and secured in the shaft, the said strip engaging said means to prevent the dislodgment thereof.

19. The combination of a member, a second member slidably mounted thereon, a stop for limiting the movement of the second member, a member having a head, said member securing the stop upon the shaft, the said stop engaging the said means to prevent the rotation thereof.

In testimony whereof, I hereunto affix my signature in the presence of two witnesses.

FRANK S. INGOLDSBY.
